Primary Examiner — Karen S Acker*Assistant Examiner* — Katrina Gonzalez*(74) Attorney, Agent, or Firm* — Vladimir Vitenberg**(57) CLAIM**

The ornamental design for an electric toothbrush, as shown and described.

DESCRIPTION

FIG. 1 is a perspective view of an electric toothbrush;

FIG. 2 is a front view thereof;

FIG. 3 is a left side view thereof;

FIG. 4 is a rear view thereof;

FIG. 5 is a right side view thereof;

FIG. 6 is a top plan view thereof; and,

FIG. 7 is a bottom plan view thereof.

The broken lines depict portions of an electric toothbrush that form no part of the claimed design.

1 Claim, 4 Drawing Sheets(56)
